ARLINGTON MOORE, OF NEW YORK, N. Y.

PROCESS OF INFOLDING PAPER-CONTAINER BODIES AND THE LIKE.

Application filed June 21, 1926. Serial No. 117,544.

My invention relates to a process of infolding paper container bodies and other bodies or shells of paper or paper-like material. The process is adapted for forming 5 a reenforced margin on paper shells of cylindrical, conical and other forms, and is also adapted to the formation of interlocked seams between such shells or bodies and inserted flanged heads, as in the case of making 10 interlocked heading joints or seams for paper container.

The present invention provides an extremely simple and efficient way of insuring 15 that the original free edge—or raw edge as it is sometimes called—of the shell shall be turned in so as to become buried within the inturned folds, as in the case of the shell with reenforced margin, or within the seam or joint in the case of interlocked seams between shells and container heads. The advantages of thus disposing of the raw edge 20 are numerous and include putting the raw edge out of sight, thereby enabling the production of a finely finished and good ap- 25 pearing product not possible with the raw edge exposed, the elimination of edge capillarity, which is of importance in containers to hold liquids, added strength and rigidity, and related features of advantage.

30 In my Patent No. 1,413,759, granted April 25, 1922, I have shown a mode of tucking the raw edge in by means of a tool provided with a terminal hook. The present process accomplishes a similar result in a much sim- 35 pler way and entirely eliminates the hook and the somewhat complicated movements and manipulations incident to its use, and is more certain and efficient in operation.

When a paper shell is rotated relatively 40 to a suitably arranged edge turning tool, the edge of the shell will be spun or turned in progressively so long as the tool is advanced gradually, and if the edge turning tool comprises a finger extending down within the 45 shell, this turned in part can be made to lie flat against the interior of the shell, or, in other words, parallel thereto, with the raw edge exposed at the inner or leading edge of the inturned fold.

50 I have found that with the same turning tool and having a simple unhooked finger, such inturned portion can be inturned bodily by a relatively quick or sudden advance of the turning tool with respect to the relatively rotating body or shell of paper, thus 55 converting a two-fold margin into a triple

folded margin in which the part, which was first turned inwardly by progressive advance of the turning tool, is directed backwardly, bringing the raw edge into the interior of 60 the triple fold so produced. At the time of the sudden or quick advance of the folding or turning tool, if the pressure finger extending within the shell is moved inwardly, or toward the shell axis a sufficient distance 65 it will accommodate the additional inturned thicknesses and press it flat.

A like result can be obtained where an interlocked joint is to be produced between a shell and an inserted flanged head, but in 70 this case there are, of course, a greater number of thicknesses of paper to be accommodated between the pressure finger and the shell and such finger is, therefore, to be moved inwardly a correspondingly greater 75 distance.

By utilization of this principle, as by repeated applications of the quick advance of the turning tool and by variations in the point at which and extent to which applied, 80 a great variety of infolds can be produced in paper articles in order to meet the requirements which may be presented, but in all cases the raw margin is infolded and buried or embedded within the multiple fold 85 of the paper, without the necessity of utilizing hooks or guides or other devices to guide the raw edge into the desired infolded and embedded position.

The accompanying drawings illustrate the 90 steps of the process and sufficient apparatus for showing how the process can be carried into effect, but the apparatus shown is illustrative only and various mechanisms, preferably automatic machines, may be used. 95

In said drawings, Fig. 1 is a fragmentary longitudinal section of apparatus designed to form a triple fold reenforced shell margin at one end of a paper container body and to form an interlocked five fold heading 100 seam at the other end.

Fig. 2 is a detail view of the forming tool release arm.

Fig. 3 is a view similar to a part of Fig. 1, and showing the parts in position prior 105 to release of the spring actuated turning tool.

Figs. 4 and 5 are enlarged sections repeating the showing of that part of Fig. 1 relating to the forming of an interlock seam, 110 with the apparatus omitted from the showing.

Figs. 6 and 7 are plan views showing how the inturned tool and finger are moved in to accommodate additional inturned thicknesses of material.

6 Fig. 8 is a section of a quadruple inturned paper shell margin.

Fig. 9 is a section of a triple inturned paper shell margin pressure formed into a reenforced neck of a paper container of the 10 firkin type and provided with a seat adapted to receive a disk lid.

Fig. 10 is a section of a sextuple fold head joint or seam for a paper container with the parts consolidated into a solid 15 coherent mass of permanent gage dimension.

Fig. 11 is a section of a consolidated five-fold interlock heading seam.

Fig. 12 is a section of a seven fold interlock seam.

20 In referring to the various folded seams, I prefer to designate same by the number of thicknesses therein and to include the non-folded shell or body part, though this part is strictly not folded.

25 In the showing of Fig. 1, the paper shell 20 is held in a chuck 22 by a plug 24, which rotates with the shell and chuck and forms an abutment for the flanged bottom 26. Chuck 22 is shown as rotatable and the tools 30 as non-rotatable, though this relation may be reversed, if desired, or both may rotate in opposite directions or/and at differing speeds. As shown, chuck 22 turns on ball bearings 28, 30 and is driven by a gear 32 meshing with gear teeth 34 on the chuck 22. 35

The shell 20 projects beyond the ends of the chuck to provide projecting material for formation into the reenforced margin or seam.

40 A turning tool 40 is arranged to extend across the projecting shell edge on a chord of the circle defined by such projecting edge (see Figs. 6 and 7). In the form shown, such tool is made of a piece of round drill 45 rod, but tools of other forms may be used.

On its inner end the turning tool is provided with or extended to form a finger 42 adapted to make contact with the inner side of the folds as they are inturned and to 50 press same flat, or in other words, to complete the turning movement through substantially 180°. This finger 42 is smooth and substantially straight and has no hook or similar arrangement for tucking in the 55 raw edge.

Provision is made for moving tool 40 to bring finger 42 thereof radially in and out and for applying sufficient pressure to fold the paper into flat folds, and in the simple 60 illustrative apparatus shown for hand operation, this is accomplished by mounting the turning or folding pin 40 to turn in a bearing 44 in a bracket 46, and providing a hand operated handle 47 and an adjustable stop 47' 65 for limiting the outward movement of pin 40

and its finger 42. Means are also provided for moving the tool 40 and attached finger 42 in a direction parallel to the longitudinal axis of shell 20. As shown, bracket 46 is clamped on a reciprocable slide bar 48 adapted to slide without turning in a slide bearing 50. The slide bar 48 can be given an axial movement of advancement and retraction by means of the toothed sector 52 meshing with rack teeth 54 formed in slide bar 48. As 70 shown, this sector 52 is hand operated, being operated by the handle or crank 56.

The rapid advancement of slide 48 and tool 40 is produced by means of the expansion spring 58, which encircles slide 48 between bracket 46 and bearing 50. A collar 60 limits the advance movement of slide 48 by contact with bearing 50. In order to divide the movement into suitable steps or parts, I may provide one or more insertable 80 and removable stop and release devices, as the swinging arm 62 having a stop head 64, adapted to be inserted between bearing 50 and collar 60 (see Fig. 3) or to be swung aside (Figs. 1 and 2) by pulling on the counterweight or handle 65, thus permitting slide 48 to be advanced by spring 58 from the position of Fig. 3 to that of Fig. 1. An adjustable stop 66 serves to limit the retractile movement of slide 48. Pin 68 in 90 bearing 50 is pressed inwardly by leaf spring 70 and is adapted to lock slide 48 in retracted position by entering a hole 72 therein. The slide may be released by lifting pin 68 by means of knob 74. 100

At the beginning of the operation, with the apparatus described, and having reference now to the inturning of the edge of the shell alone without the inserted flanged head, the operator grasps crank 56 in one hand 105 and pulls out stop pin 68 with the other to release slide 48. He then backs off gradually with handle 56 and thereby permits pin 40 to be advanced by expansion of spring 58 against the edge of the rotating shell 20, 110 while he holds the finger 42 by means of handle 47 against the inturning edge and forms a flat fold, and thus performs the operation illustrated in Fig. 3. While this gradual advance of pin 40 is taking place 115 the shell is rapidly rotating, and a considerable number, say 50 to 100, revolutions of the shell may take place during this interval in which the turning pin is gradually advanced, this step being terminated by the 120 collar 60 of slide 48 coming to rest against the hinged stop piece 64, which is held up against the slide bar 48 by the counterweight 65. (See Fig. 3.) The stop 47' prevents pushing handle 47 and finger 42 125 too far in the operation of holding finger 42 against the fold 104 as the latter is being turned in, while the gradual advance of pin 40 is taking place.

To perform the second step which is the 130

principal feature of the present invention, the operator still holding handle 47, but having moved it to bring the finger 42 inwardly somewhat from the position of Fig. 6 for the first step to that of Fig. 7 to accommodate additional thicknesses of paper, releases crank 56 of sector 52, and pulls on handle 65 of hinged stop arm 62, thereby withdrawing stop head 62 from between the collar 60 and shaft bearing 50. This releases slide 48, which upon being released is abruptly advanced by the spring 58 from the position shown in Fig. 3 to that shown in Fig. 1. This advance, instead of being gradual and distributed over a larger number of shell rotations, is quick and abrupt and probably is complete in considerably less than a single rotation of the shell. Its effect is to form a new fold line 102 at the place where the advancement of pin 40 is stopped, as in the case under discussion, such abrupt advance is stopped by collar 60 coming into contact with slide bearing 50.

With the abrupt advance of the turning pin, there is no longer a gradual progressive turning over of the paper of the shell, but everything outside the new fold line is folded in bodily at the new fold line and this bodily folding over is completed by the finger 42. In the case of the paper having first been gradually turned or spun into a double fold with the raw edge opposite or substantially opposite the new fold line, the resulting product after the abrupt turn is completed will be a triple fold margin, as shown at the upper right hand part of Fig. 1, with the originally folded in part 104 turned backward and the raw edge buried immediately inside the new fold line. Stated differently, the triple fold margin will include three thicknesses, the container body wall thickness 105 at the outside, the inturned fold part 106 on the inside, and the original margin fold 104 extending reversely between them and with the raw edge buried or embedded within the space between the inner and outer folds.

Such triple inturned fold has many uses. In Fig. 9, for example, I have shown same comprising folds 104', 105' and 106', shaped by suitable shaping or spinning tools into a reinforced firkin margin with an internal lid seat 107 adapted to receive a disk lid, and it will be seen how with such construction capillarity absorption of liquids contained in the container is precluded by the raw edge being removed entirely from any possibility of contact therewith.

In Fig. 8 I have shown a quadruple folded marginal part comprising folds 108, 110, 112 and 114, which can be provided by performing a second abrupt inturning operation such as described, and it will be apparent that many variations can be produced by varying the number of folds, the width and

order of folds, and the place or places where the various fold lines are located.

The operation is much the same where an inserted flanged head is to be formed into a joint or seam with the margin of a paper shell. The formation of the simplest form of joint so made up is illustrated at the left hand end of Fig. 1, and in Fig. 5. Here the original shell margin 200 extends beyond the flange margin 202 and is spun in thereto by the customary gradual spinning operation as shown at the lower left hand part of Fig. 1, and as shown in Fig. 5 in full lines at the upper right hand part of the figure.

When the abrupt infolding is done on a new fold line located at about the middle of the flange height, the resulting folded joint is of the quintuple type shown at the upper left hand part of Fig. 1, and in dotted lines in the right hand part and in full lines at the left hand part of Fig. 5, including, interlocked with the triple folded parts 200, 204, 206 of the shell, the double folded parts 202, 203 of the head or bottom flange. In Fig. 11 I have shown the completed five fold joint or seam comprising folds 200', 204' and 206' of the body wall and folds 202' and 203' of the lid flange formed by folding as in the left hand side of Fig. 1 and in Fig. 5 followed by the application of consolidating pressure by means of a tool or die having a terminal bead to produce the internal groove 210. The production of the finished seam, however, may be accomplished in a variety of ways after the infolding process of the present invention is completed.

As in the case of the simple folded shell margin the folded seam including shell and lid flange may be produced in a variety of forms depending on the number of abrupt turns and location of abrupt turn or fold lines. For example, the form 212 of Fig. 12 having seven thicknesses is produced by making a second abrupt fold of a suitably extended lid flange and body wall. The form 214 of Fig. 10 having six folds is produced by extending the shell margin considerably beyond the lid flange and gradually spinning the shell material back upon itself before infolding with the lid flange, and various other forms may be produced in carrying out the principle of the invention.

I claim:

1. The process of making a multiple fold margin on a shell of paper, which consists in rotating same relative to a spinning tool, advancing the tool gradually relative to the shell to fold in the margin, and then advancing the tool abruptly, whereby the turned in raw edge is reversed and a fold produced in which the raw edge is enclosed between folds or thicknesses of paper.
2. In the process of multiple infolding the wall of a paper shell, the steps of turning in the margin, and then abruptly turn-

ing over the infolded margin and adjacent shell wall together.

3. The process of infolding the margin of a paper shell into multiple substantially parallel folds, which comprises rotating the shell with respect to a spinning tool extending across the edge of the shell and inwardly of the shell substantially parallel to the shell walls, advancing the tool relative to the 10 rotating shell to turn the margin inwardly, and then abruptly advancing the spinning tool with respect to the rotating shell and moving the inwardly extending tool part toward the shell axis to accommodate additional 15 thicknesses of paper, whereby the previously infolded margin and adjacent shell wall are turned in bodily on a new fold line with the original edge of the shell between the folds and directed in the same sense as 20 originally.

4. In the process of making folded margins on paper shells, the step of abruptly advancing a spinning tool relatively to a relatively rotating shell having its edge previously 25 turned in, whereby the turned in edge and adjacent wall portion are bodily reversed on a new fold line.

5. The process of making on paper shells an infolded margin having, with the inclusion 30 of the adjacent wall part, three folds, which includes the step of inturning the edge of the shell, and then abruptly infolding the inturned edge and adjacent wall part, whereby these parts are reversed on a 35 new fold line and the turned in edge is enclosed in the middle of the triple fold.

6. The process of making on paper shells a multiple infolded margin having, with the inclusion of the adjacent wall part, an odd 40 number of folds, which includes the steps of infolding the margin, and then abruptly infolding the wall and inturned margin on a new fold line, whereby the previously inturned part is reversed, and repeating the 45 last named step.

7. In the process of making a multiple fold interlocked seam between a paper shell and a flanged head, the steps of turning in the edge of the shell with the head flange 50 between the shell wall and the inturned edge part, and abruptly turning in the inturned parts on a new fold line, whereby the pre-

viously inturned parts are reversed and an interlocked seam is produced.

8. In the process of making a multiple fold interlocked seam between a paper shell and a flanged paper head, the steps of advancing a spinning tool relatively to the relatively rotating shell edge and thereby turning in the shell edge with the lid flange 60 between it and the shell wall, and then abruptly advancing the spinning tool relative to the relatively rotating shell and head flange, whereby the previously inturned parts are abruptly reversed and an interlocked seam is produced. 65

9. In the process of making a multiple fold interlocked spun joint between a paper shell and the flange of an inserted flanged paper head, the steps of inturning the edge of the 70 shell over the edge of the head flange by advancing a spinning tool relatively thereto while shell and head are being rotated with respect to the spinning tool, and then abruptly advancing the spinning tool relatively to the relatively rotating shell and head, whereby the edge of the head flange, the inturned shell edge and the adjacent shell wall are abruptly reversed on a new fold line and an interlocked seam is produced. 75

10. In the process of making a multiple substantially parallel fold interlocked seam between a paper shell and an inserted flanged paper head, the steps of rotating shell and head relative to a spinning tool 80 having a part extending across the end of the shell and a part extending inwardly substantially parallel to the shell wall to keep the parts substantially in parallelism, advancing the spinning tool relative to the shell and head to turn the edge of the shell in over the edge of the head flange and then abruptly advancing the spinning tool relative to the relatively rotating shell and head and moving the inwardly extending tool inwardly toward the shell axis to accommodate extra thicknesses, whereby the inturned edge, the head flange and adjacent shell wall are abruptly inturned in reverse relation and an interlocked seam produced with the 90 folds thereon in substantial parallelism. 95

In testimony whereof, I have signed my name hereto.

ARLINGTON MOORE.
